UNITED STATES PATENT OFFICE

SAMUEL N. SENNA, OF CHICOOPEE, MASSACHUSETTS, ASSIGNOR TO B. F. PERKINS & SON,
INC., A CORPORATION OF MASSACHUSETTS

TESTING MACHINE

Application filed June 22, 1929. Serial No. 372,966.

This invention relates to improvements in testing machines and is directed more particularly to improvements in testing machines of the type disclosed in the patent to 5 F. P. Cleveland No. 1,025,110 of April 30, 1912.

In the apparatus disclosed in the patent referred to there is provided a co-operating specimen platform and clamp, the latter of 10 which is arranged to clamp a specimen to the platform. Both of these are provided with a central aperture therethrough and a yieldable diaphragm below the platform is distended by fluid pressure through the platform aperture so as to rupture the specimen 15 therebetween which constitutes the test of the specimen.

Such machines are employed for testing specimens of web material like paper and 20 cardboard ranging in thickness from a few thousandths of an inch for thin paper to a considerable thickness like that of corrugated board. It is desired that all specimens be firmly clamped between the clamp and platform 25 and with a more or less even pressure. It will be appreciated that with the parts arranged for moving the clamp and platform towards and away from one another a definite distance that the clamping action will differ 30 when clamping specimens of different thicknesses. As for example if the parts are arranged to properly clamp a thick specimen such as corrugated board a thin specimen would be clamped improperly. Likewise an 35 adjustment for thin paper would tend to unduly press upon and even crush a much thicker specimen.

The principal object of this invention is 40 the provision of novel mechanism for effecting a relative movement of the specimen clamping members of a testing machine which is adjustable to vary the movement thereof whereby the apparatus may accommodate specimens of different thicknesses and 45 thereby attain the desired clamping effect without injuring the specimen.

The objects are accomplished by means of 50 the novel combinations and arrangements of parts to be more fully described in the form of the invention at present preferred and

illustrated in the accompanying drawing in which:

The figure is a partial side elevational view of a testing machine embodying the 55 novel features of the invention.

Referring to the drawing the invention will now be described in detail.

A frame of a testing machine of the type shown in the patent referred to is represented at F. A platform P associated therewith 60 has a central aperture below which is disposed a distendable diaphragm D. As in the patent referred to the diaphragm is distended by fluid pressure to rupture a specimen clamped to the platform by a clamp C. 65

The clamp has upwardly extending arms 2 connected to a hub 4 carried at the lower end of a rod R which is reciprocable in the frame F.

A reciprocation of the rod will move the 70 clamp towards and away from the platform. To operate the clamp and rod through various distances for clamping specimens of different thicknesses and to lock the clamp in clamping position the novel features of the 75 invention are directed and will now be described.

A head 10 fixed to the upper end of the rod is provided with a slot therethrough for receiving a clamp actuating lever 12 pivoted 80 at 14 to the frame F. A shaft 16 rotatable in the head has fixed thereto a cam member 18 which lies within the slot of the head so as to be rotatable therein by a rotation of the shaft. The cam underlies the lever 12. As will be seen the cam is provided with a non-concentric peripheral surface. That 85 is it has a plurality of peripheral points 19, 20 and 21 which are of different distances from the axis of the shaft. A spring 22 disposed between the head and frame urges the rod upwardly so that the cam engages the underside of lever 12 to urge it upwardly to its upper position shown. It will be readily 90 obvious that according to the setting of the cam the clamp C will when in its upper position assume positions at various distances or heights above the platform.

It is preferable that the lever 12 swing 95 through a constant angle so that with the

clamp at these various heights it will be moved by the operation of the lever 12 through a constant distance. The cam is arranged to locate the clamp nearer the platform for thin specimens than for thicker specimens, wherefor equal pressure may be maintained and a thick specimen clamped without injury.

A cam lever 30 may be fixed to the shaft 16 to facilitate the rotation thereof while designating characters A, B, C on the head 10 co-operate with a pointer 32 of the lever to indicate whether the cam is set for clamping thick, thin or intermediate specimens.

Of course instead of the characters shown lettering may be employed such as paper, corrugated board, etc. Cams of other forms may be employed to vary the relative position of the parts all within the spirit of the invention.

Mechanism for operating the lever 12 will now be described. An operating lever 40 is pivoted at 42 in a lug F' of the frame F and carries on its outer end a handle 44. A link 46 is pivoted at opposite ends as at 48 and 50 to the levers 12 and 40 so that as lever 40 is oscillated the lever 12 is swung up and down so as to move the clamp into and out of clamping position.

In operation the lever 40 is swung in a clockwise direction to move the clamp into clamping position and reversely for unclamping. In clamping position the levers and link assume the position shown in dot-dash lines. The parts are preferably so arranged that in this position the end of lever 12 may abut the lug F' of the frame while the pivotally connected levers 12 and 40 and link act as a toggle to lock the parts in position whereby the clamp is locked in lower clamping position.

I am aware that many changes may be made in the form of the invention without departing from the spirit and scope thereof and I prefer therefore to be limited by the appended claims rather than by the foregoing description.

What I claim is:

1. A testing machine comprising, a frame, a clamp rod slidable therein, a lever pivoted to said frame, a cam member rotatable on said rod and underlying said lever, an operating lever pivoted on said frame, and connections between said levers.

2. A testing machine comprising in combination, a frame, a clamp rod slidable in said frame, a lever pivoted in said frame at one side of said rod and which extends transversely of the axis of said rod, an operating lever pivoted to said frame at the opposite side of said rod, connections between said levers, and a cam member rotatable on said rod and underlying said first-named lever.

3. A testing machine comprising in combination, a frame, a clamp rod slidable in

said frame, a lever pivoted at one end to said frame and at one side of said rod and extending transversely of the axis of said rod, an operating lever pivoted to the said frame at the opposite side of said rod, connections between the other end of said first-named lever and said operating lever, and a cam rotatable in said rod and which has portions underlying said first-named lever and engageable therewith.

4. A testing machine comprising, a frame, a clamp rod slidable therein, a lever pivoted to said frame, a cam member rotatable on said rod and underlying said lever, means to rotate said cam member, an operating lever pivoted on said frame, and connections between said levers.

5. A testing machine comprising, a frame, a clamp rod slidable therein, a lever pivoted to said frame, a cam member rotatable on said rod and underlying said lever, means yieldingly acting on said rod to yieldingly urge said cam into engagement with said lever, an operating lever pivoted on said frame and connections between said levers.

In testimony whereof I affix my signature.
